VEHICLE BODY

Paul B. Porter, Chambersburg, Pa.

Application July 1, 1949, Serial No. 3,653

Term of patent 14 years

(Cl. D14—3)

To all whom it may concern:

Be it known that I, Paul B. Porter, a citizen of the United States, residing at Chambersburg, State of Pennsylvania, have invented a new, original, and ornamental Design for Vehicle Bodies, of which the following is a specification, reference being had to the accompanying drawing, forming a part hereof.

Fig. 1 is a perspective view of the vehicle body according to the design;

Fig. 2 is a side view of the vehicle body;
Fig. 3 is a rear view thereof, and
Fig. 4 is an enlarged view from above partially broken away.

I claim:

The ornamental design for a vehicle body, substantially as shown.

PAUL B. PORTER.
